UNITED STATES PATENT OFFICE.

LEWIS L. HYATT, OF NEW BRUNSWICK, NEW JERSEY.

DESIGN FOR RUBBER BOOTS.

Specification forming part of Design No. 6,957, dated October 14, 1873; application filed May 10, 1873.
[Term of Patent 14 years.]

To all whom it may concern:

Be it known that I, LEWIS L. HYATT, of New Brunswick, in the county of Middlesex and State of New Jersey, have invented a new and original Design for Rubber Boots, of which the following is a specification:

The accompanying drawing fully represents my improved design, which consists of the foot portion A of the boot, finished with the ordinary smooth rubber surface, and the leg portion, embossed or pebbled, and thus made to have the appearance of leather, which is

much neater and more stylish than the smooth rubber leg.

I claim as my invention—

The design for a rubber boot, consisting of a smooth surface for the foot and an embossed surface for the leg, substantially as shown and specified.

LEWIS L. HYATT.
